UNITED STATES PATENT OFFICE.

GEORGE HOLT FRASER, OF BROOKLYN, NEW YORK.

CRUSHING MACHINE.

Original application filed December 31, 1907, Serial No. 408,773. Renewed June 12, 1916, Serial No. 103,341. Divided and this application filed February 2, 1917, Serial No. 146,220. Renewed June 14, 1922. Serial No. 568,237.

To all whom it may concern:

Be it known that I, GEORGE HOLT FRASER, a citizen of the United States, residing in the borough of Brooklyn, county of Kings, 5 city and State of New York, have invented certain new and useful Improvements in Crushing Machines, of which the following is a specification, being a division of my application filed Dec. 31, 1907, Serial No. 10 408,773, renewed June 12, 1916, Serial No. 103,341.

This invention relates to machines for crushing, grinding or pulverizing hard materials, and particularly to such machines 15 having a revolving ring enclosing usually three crushing rolls, in which type of machine the material is crushed between the inner face of the ring and the outer faces of the rolls, which press outwardly against the ring. Springs are usually employed to 20 press the rolls outwardly, and the rolls are usually mounted on transverse shafts, to one of which driving power is applied for rotat- 25 ing the ring and the remaining rolls by traction.

The roll shafts are carried in bearings which are usually connected around the exterior of the ring and are movable in directions radially of the ring.

30 The invention aims to provide certain improvements especially applicable to mills of this general type.

The preferred form of the invention is shown in the accompanying drawings, in 35 which,

Fig. 1 is a side elevation partly in section on the planes of the lines 1—1 in Fig. 2;

Fig. 2 is a fragmentary plane view partly broken out and partly in section approxi- 40 mately on the planes of the lines 2—2 in Fig. 1;

Fig. 3 is a face view of the dust guard, and

Fig. 4 is a fragmentary section showing 45 the dust guard in section on the lines 4—4 in Fig. 3.

The crushing ring is lettered *a*, the crushing rolls *b*, their shafts *c*, their pressure spring *d*, and the adjusting screws there- 50 fore *e*. *A* is the casing, *B* are the side covers, *C* are the bearing frames, and *D* their caps. *x* is the feed inlet.

The casing *A* encloses the ring and rolls.

Three rolls are shown, one at the top preferably yieldingly supporting the ring, and 55 the other two equally disposed within the ring. The inner face of the ring is concave and fits the outer convex face of each roll. The rolls are pressed outwardly against the inner face of the ring by the springs *d*, and 60 this pressure is adjusted by screws *e*. The pressure of the springs is transmitted to the bearing frames *C*, and by them to the shafts of the rolls. The ring and rolls are revolved by driving one or more of the rolls, or the 65 ring, the motion of the driven part being transmitted to the others by traction. Preferably the top shaft *c* is used as the driving shaft for driving the top roll, which then drives the ring, which in turn drives the 70 lower rolls. Preferably all the rolls are movable radially of the ring, and the ring is movable radially of the rolls, so that the 75 parts are free to yield to vibration or to adapt themselves to the work between their crushing faces. Thus the ring is a revolving annular die which receives on its inner face the rock to be crushed, and the rolls are revolving crushing rolls which crush the rock against the inner face of the ring.

The bearing frames *C* are preferably sectionalized, and according to one feature of the preferred form of my present improvements are composed of a plurality of relatively movable members *T* and *U* affording 85 *U*-shaped frames which pass around the outer side of the ring, preferably exterior to the casing, to connect the opposite bearings to hold them in line, while permitting the roll and shaft to move radially of the ring, 90 and also laterally or axially. Each of the lower bearing frames is preferably formed with an integral ear which is hung to the casing at *f*, preferably above the rolls by a swinging suspension link *V*, so that the 95 frame can swing inwardly and outwardly with the radial movement of the rolls.

Each of the bearing frames is preferably formed with a hinged cap *D* connected to it by a single bolt *g* at each side of the bearing, these bolts being preferably parallel with the shafts, so that when the bolts traverse the ears *h* on the frames and *i* on the caps, there is no possibility of the caps being 100 displaced relatively to the frames in direction radially of the shafts when the parts 105

are assembled, as would be the case if the bolts were disposed at right angles to the shafts, although they may be so placed if desired.

5 Each frame C preferably is provided with a thrust member, preferably a roller *j*, which strikes against a fixed part on the casing to limit axial movement of the frame. This roller is preferably arranged to permit the 10 frame to have a slight axial movement under end thrust of the shaft.

Each frame is preferably made with a thrust face *k* definitely located relative to the thrust member *j*, and has a bearing socket 15 *l* which is preferably bored cylindrically, but may be bored as a segment of a sphere.

In this socket is shown a bearing member H, which has a spherical or partially spherical external portion fitting the socket *l*, so 20 that the bearing member can oscillate therein after the manner of a universal joint to adapt itself to the shaft. The member H may be a tubular casting, but I prefer to form it in halves. It may be of bearing 25 metal and constitute itself the antifriction bushing for the shaft, but I prefer to form it with a cylindrical bore *m* and to insert two removable semi-cylindrical sleeves or bushings of Babbitt metal *n* within it for 30 carrying the shaft. The upper half *o* of the member H is formed with an oil well *p* and the lower half *q* is formed with a shoulder *r*, and both halves when bored are finished on a line with this shoulder, which engages 35 the end *k* of the frame C, and limits the inward position of the member H. The outer face of this member is formed with a thrust face *s* for the thrust collar *t* of the shaft.

40 A dust guard I preferably surrounds the shaft at the inner end of each bearing, and has a tubular projection J, preferably round or formed as a segment of a sphere on its outer side, which fits into the bore of the member H and is supported thereby so that the dust guard can slide axially of the member, and may cant in its support as the frame rocks. Springs K fit within and without the dust guard and react against the bearing member, serving to keep the dust guard pressed against the side of the casing to close the shaft slot thereof. The dust guard shown has enlarged or oval apertures L through it for passing over the shaft with sufficient clearance to permit travel of the latter as it wears into the bushings, and has an outer wall M adjacent to the bearing, and a chamber N between its two walls. In this chamber are movable or sliding members 55 sustained slidingly on the shaft, which are preferably two sliding plates *s'* kept apart by a spring or bar *t'*. The plates *s'* have bores fitting the shaft and are free to float with the movements of the shaft relatively to the 60 dust guard. They are pressed against the

opposite faces of the guard and close the clearance openings therethrough from the casing on one side and the bearing on the other side. They are so thin and slight that they are practically passive members adapting themselves to the shaft, and do not exert sufficient pressure thereon to groove the shaft. The spring or bar *t'* holds them spaced apart, and the space within this spring constitutes a stuffing box into which waste or packing may be rammed through the side apertures *u*.

70 The dust guard slides against the side of the casing with the movements of the bearing frames, and its plates *s'* slide within it with the wear of the shaft into the babbitt. Projections *v* preferably on the dust guard afford stops or faces for engaging similar 80 stops or faces on the bearing or frame to prevent the dust guard from rotating, as 85 best seen in Figs. 3 and 4.

90 The casing is preferably divided horizontally and vertically through its middle in the plane of the axis of the die into upper and lower sections and into front and rear sections, and vertically in the plane of the lateral center of the rolls into right hand and left hand sections so that the frame proper of the casing comprises eight separably connected removable parts or segments, the front ones being lettered F¹ F² F³ and F⁴ respectively, and the rear ones being lettered G¹ G² G³ and G⁴ respectively, which are removably connected together forwardly and rearwardly by horizontal bolts *x'* traversing ears *z'* on the base or lower sections, and *z''* on the top or upper sections, and sideways by horizontal bolts *y'*, and vertically by vertical bolts *u'*, as shown in Figs. 95 100 and 2, and these sections are preferably each formed with an integral side wall *w* on each side having an arc-shaped inner edge which when the members are assembled affords an enlarged opening *z* on the opposite 105 sides, which openings are closed by the covers B to afford a crushing chamber for the 110 ring and rolls.

115 The preferred form of my invention is shown in Figs. 1 and 2, which show a construction particularly adapted to sectionalized machines, in which each movable non-rotative bearing member or frame C comprises a spring actuated or pressed member or yoke T which is pivotally movably mounted and preferably hinged or fulcrumed to the casing, and preferably pivotally movably and removably mounted non-rotative bearing means on which the rolls are rotatably mounted, and which are preferably hinged to and swing from the yoke T at each side of the casing, as the bearing frames U which are held guided positioned or supported by links V, the pivoted ends of the frames being widened if 120 125 desired to bear against the sides of the rock- 130

ing yokes to give any desired rigidity of the frame axially of the shafts. In this construction two thrust rollers j will be supplied for each frame U , so that the latter 5 may rock relatively to the shaft until these rollers strike the casing. In this construction the spring seat i extends within the spring to bring the adjusting screw as near as possible to the casing to diminish the 10 rocking action of the spring during movement of the rocker T , and the pressure spring d is opposite and actuates the spring pressed member T and reacts on the casing, and the stress of the spring is transmitted 15 by the member T to the movable non-rotative means U which are shown as tension members, swingingly connected to the yoke T so that they can move relatively thereto to follow the radial movement of the roll 20 mounted on them while transmitting the stress of the spring acting to hold the roll outwardly to resist a crushing pressure from the inner face of the die.

Preferably the members T are hinged to 25 the casing on horizontal axes parallel with and outwardly of the axes of the rolls by pivotal pins f^1 , which as shown are respectively above the upper roll and laterally of its pressure spring and below the lower 30 rolls and beneath their pressure springs, but they may be otherwise disposed as desired.

As shown the non-rotative means U are pivotally mounted on the rockers T on axes outwardly of and parallel with the axes of 35 their rolls, and above the upper roll and below the lower rolls respectively, by pivotal pins f^2 parallel with the axles or shafts c and spaced at each side of the pressure springs and outwardly of the casing, but 40 they may be otherwise disposed if desired. With the arrangement shown any bearing member U may be removed axially of its shaft by withdrawing its hinge pin f^1 and swinging its outer end clear of the yoke, 45 whereupon after removing the thrust collar t and disconnecting the link V the bearing member U may be slid axially off the end of the shaft for any purpose and in reverse manner it may be placed again in position.

50 By this modification, the parts may be made extremely light, so that they can be adapted for packing or mule-back transportation.

The roll b is of improved construction, 55 preferably consisting of a soft iron hub X bored to fit the roll seat on the shaft c , and held against the shoulder on this shaft by the flanged roll collar Y , which embraces the outside of this shoulder and projects 60 into recesses in the roll, and is connected thereto by bolts traversing it and the roll to hold the roll on the seat, which hub has an external finished face and shoulder, on which face is forced a shell or tire W of hard material, preferably tempered steel,

which is shaped to seat on and fit the hub and is riveted on the hub by swaging over the latter or otherwise to prevent loosening. It may be notched or key-seated, and the hub may be swaged into the notches, or may 70 carry a key to ensure against the tire turning on the hub, but as it is applied to the hub under great pressure, this may not be necessary in some cases, and I prefer to rely on a tight fit between the cylindrical faces 75 of the hub and tire, and leave an integral thrust shoulder at one end of the hub, and to swage the hub against the tire at the other end for securing the parts, or use a clamp.

80 Shaft slots a' as shown in Fig. 1 are formed in the casing or cover preferably by providing them in the removable covers B .

The wall of the casing and the opposite wall of the cover are machined to receive 85 wear pieces P which prevent the ring from coming in contact with the casing.

In operation, the feed is directed onto the revolving ring, being crushed between the ring and rolls and discharged through the 90 bottom of the casing.

In case the bearing frames are out of line or oscillate, the bearing members rock in the frames and preserve parallelism with the shaft. The dust guards slide in the 95 bearing members during motion of the latter. The weight of the suspended lower bearing frames is so nearly balanced that the springs determine the crushing pressure irrespective of the weight of the yokes. 100 The sections of the frame or casing can be shipped separately and individually, or partially assembled as conveniences dictate, and these can be removed individually or as a group. If desired the front sections can be 105 withdrawn from the rear sections upon releasing their connecting bolts x' and the cover screws and the pins g of the front bearing caps D , so that the front section and bearing frame can be withdrawn from 110 or applied to remaining parts without otherwise disturbing these.

The rolls will move inwardly and outwardly toward and from each other to adapt themselves to the material being 115 crushed on the inner face of the ring, against which face these will be pressed by the pressure springs. The bearing frame will be swingingly sustained or positioned by the links V and the removable yokes T on which 120 they are pivotally mounted, and these yokes can be disconnected and separately moved back to replace a pressure spring.

It will be seen that my invention provides improvements which can be readily 125 and advantageously availed of, and it will be understood that the invention is not limited to the particular details of construction, arrangement and combination of parts set forth as constituting its preferred form, 130

since it can be employed in whole or in part according to such modifications as circumstances or the judgment of those skilled in the art may dictate, without departing from the spirit of the invention.

The end bearing member may be faced off at right angles to its bore, and a ball or roller may be carried by the dust guard, or the dust guard may be correspondingly 10 faced off, so that the end of the bearing member may strike against the ball or roller, or against the dust guard to limit end thrust.

What I claim is:

- 15 1. In combination, an annular die revolving in an approximately vertical plane and having an internal crushing face, a movable and rotatable crushing roll within and eccentric of said die and having a peripheral crushing face reciprocal to the inner face of said die, means for revolving one of 20 said parts, a casing supporting said parts, a movable member movably mounted on said casing, non-rotative movable means on 25 which said roll is rotatably mounted and movably mounted on and held outwardly by said movable member, and pressing means opposite and reacting on said movable member and said casing for holding said 30 non-rotative means outwardly to hold said roll outwardly toward the inner face of said die to resist a crushing pressure therefrom.
2. In combination, an annular die revolving in an approximately vertical plane and 35 having an internal crushing face, a movable and rotatable crushing roll within and eccentric of said die and having a peripheral crushing face reciprocal to the inner face of said die, means for revolving one of 40 said parts, a casing supporting said parts, a movable member movably mounted on said casing, non-rotative movable means on 45 which said roll is rotatably mounted and pivotally mounted on and held outwardly by said movable member, and pressing means acting on said movable member and reacting on said casing for holding said 50 non-rotative means outwardly to hold said roll outwardly toward the inner face of said die to resist a crushing pressure therefrom.

- 55 3. In combination, an annular die revolving in an approximately vertical plane and having an internal crushing face, a movable and rotatable crushing roll within and eccentric of said die and having a peripheral crushing face reciprocal to the inner face of said die, means for revolving one of 60 said parts, a casing supporting said parts, a movable member movably mounted on 65 said casing, non-rotative movable means on which said roll is rotatably mounted and pivotally mounted on a horizontal axis on and held outwardly by said movable member, and pressing means acting on said movable member for holding said non-rotative means

outwardly to hold said roll outwardly toward the inner face of said die to resist a crushing pressure therefrom.

4. In combination, an annular die revolving in an approximately vertical plane and 70 having an internal crushing face, a movable and rotatable crushing roll within and eccentric of said die and having a peripheral crushing face reciprocal to the inner face of said die, means for revolving one of 75 said parts, a casing supporting said parts, a movable member movably mounted on said casing, non-rotative movable means on which said roll is rotatably mounted and movably connected to said movable member outwardly of the axis of said roll, and pressing means for holding said roll outwardly toward the inner face of said die to resist a crushing pressure therefrom opposite and reacting on said movable member. 80

5. In combination, an annular die revolving in an approximately vertical plane and having an internal crushing face, a movable and rotatable crushing roll within and eccentric of said die and having a peripheral 85 crushing face reciprocal to the inner face of said die, means for revolving one of said parts, a casing supporting said parts, a movable member pivotally mounted on said casing, a non-rotative movable means 90 on which said roll is rotatably mounted and movably mounted on and held outwardly by said movable member, and pressing means acting on said movable member and reacting on said casing for holding said 95 non-rotative means outwardly to hold said roll outwardly toward the inner face of said die to resist a crushing pressure therefrom. 100

6. In combination, an annular die revolving in an approximately vertical plane and having an internal crushing face, a movable and rotatable crushing roll within and eccentric of said die and having a peripheral 110 crushing face reciprocal to the inner face of said die, means for revolving one of said parts, a casing supporting said parts, a movable member pivotally mounted on a horizontal axis on said casing, non-rotative 115 movable means on which said roll is rotatably mounted and movably mounted on said movable member, and pressing means for holding said roll outwardly toward the inner face of said die to resist a crushing pressure therefrom opposite and acting on 120 said movable member and reacting on said casing. 125

7. In combination, an annular die revolving in an approximately vertical plane and having an internal crushing face, a movable 125 and rotatable crushing roll within and eccentric of said die and having a peripheral crushing face reciprocal to the inner face of said die, means for revolving one of said parts, a casing supporting said parts, a mov- 130

able member pivotally mounted on said casing on an axis above the axis of said roll, non-rotative movable means on which said roll is rotatably mounted and movably mounted on said movable member, and pressing means for holding said roll outwardly toward the inner face of said die to resist a crushing pressure therefrom reacting on said movable member.

10 8. In combination, an annular die revolving in an approximately vertical plane and having an internal crushing face, a movable and rotatable crushing roll within and eccentric of said die and having a peripheral crushing face reciprocal to the inner face of said die, means for revolving one of said parts, a 15 casing supporting said parts, a movable member pivotally mounted on said casing, non-rotative movable means on which said roll is rotatably mounted and swingingly connected to said movable member at a point outwardly of the axis of said roll, and pressing means for holding said roll outwardly toward the inner face of said die to resist 20 a crushing pressure therefrom reacting on said movable member.

9. In combination, an annular die revolving in an approximately vertical plane and having an internal crushing face, a movable and rotatable crushing roll within and eccentric of said die and having a peripheral crushing face reciprocal to the inner face of said die, means for revolving one of said parts, a casing supporting said parts, a pressure sustaining member pivotally mounted on said casing, non-rotative movable means on which said roll is rotatably mounted and movably connected to and held outwardly by said member, pressing means for holding said 35 roll outwardly toward the inner face of said die to resist a crushing pressure therefrom reacting on said member, and tensioning means opposite and for varying the tension of said pressing means.

40 10. In combination, an annular die revolving in an approximately vertical plane and having an internal crushing face, a movable and rotatable crushing roll within and eccentric of said die and having a peripheral crushing face reciprocal to the inner face of said die, means for revolving one of said parts, a casing supporting said parts, a movable pressure sustaining member movably mounted on said casing, non-rotative movable means on which said roll is rotatably mounted movably connected to said movable

member, pressing means for holding said roll outwardly toward the inner face of said die to resist a crushing pressure therefrom reacting on said movable member, and adjusting means opposite for adjusting said pressing means relatively to said movable member.

11. In combination, an annular die revolving in an approximately vertical plane and having an internal crushing face, a movable and rotatable roll within and eccentric of said die and having a peripheral crushing face reciprocal to the inner face of said die, means for revolving one of said parts, a 45 casing supporting said parts, a movable spring actuated member mounted on and movable relatively to said casing, a spring carried by said casing and opposite and acting on said member to resist movement thereof, non-rotative movable means on which said roll is rotatably mounted movable relatively to said member, and means affording a rocking connection between said non-rotative means and said member movably holding the former from the latter for holding said roll outwardly toward the inner 50 face of said die to resist a crushing pressure therefrom.

12. In combination, an annular die revolving in an approximately vertical plane and having an internal crushing face, a movable and rotatable roll within and eccentric of said die and having a peripheral crushing face reciprocal to the inner face of said die, means for revolving one of said parts, a 55 casing supporting said parts, a movable spring pressed member mounted on and movable relatively to said casing, a spring carried by said casing and opposite and acting on said member to resist movement thereof, non-rotative movable hinged means on which said roll is rotatably mounted and movable relatively to said member, and means affording a movable connection between said non-rotative means and said member for resisting the stress of said roll and holding said roll outwardly against the inner face of said die to resist a crushing pressure therefrom.

In witness whereof, I have hereunto signed my name in the presence of two subscribing witnesses.

GEORGE HOLT FRASER.
